INNER TUBE BOAT FRAME

James Wesley Ambrose, Portland, Oreg., assignor to
Earl O. Williams, Arcata, Calif.

Filed May 9, 1960, Ser. No. 27,700

5 Claims. (Cl. 115—26.3)

This invention relates to new and useful devices for supporting children in water and, more particularly, to a new and useful frame to be used in combination with an inflated inner tube.

It is well known that for many years the inflated tire tube has been a continued source of enjoyment for children when playing in water. Such devices usually available on the household premises have been employed as swimming aids, safety devices and amusement means for children in the lake, surf or swimming pool because of their good buoyant qualities. However, despite its desirable characteristics, the inflated inner tube is easily capsized and difficult to grasp when wet. For these reasons the value of the tube as a safety device is questionable, and many have come to regard it as an attractive nuisance potentially dangerous to beginning swimmers and the like. Also, because of its shape and bulk, the swimmer finds it difficult to propel the tube in water.

The preferred embodiment of the within invention provides a new and useful water vehicle for children by combining with an inner tube a frame comprising a sheet of material having a horizontal extension greater than the outside diameter of the inflated inner tube and a vertical extension greater than the outside cross-sectional diameter of the tube. This frame defines a substantially U-shaped cut out located between the vertical margin of the frame to receive the tube normal to and projected laterally on opposite sides of the frame. The cut out terminates at oppositely-disposed ends in concave margins having a radius of curvature slightly less than that of the tube. These concave margins are horizontally spaced apart a distance slightly less than the outside diameter of the tube. On the upper margin of the frame proximate the center of the tube, a seat is mounted which permits the weight of the operator to be centrally supported by the tube. The frame includes a pair of pedals for actuating a gear-driven shaft having a propeller at the rear end thereof and also includes a tiller-actuated rudder to direct the vehicle when propelled in the water.

It is a primary object of the within invention to provide a safe means for using inflated inner tubes in water. Accordingly, a frame is provided for the tube, which will extend vertically below the surface of the water to function as a keel thereby stabilizing the tube and eliminating its tendency to capsize.

It is another primary object of the within invention to provide a frame support for an inflated inner tube which permits easy propulsion of the tube through the water. To accomplish this object, the frame includes: a seat in registry with the hole of the tube to distribute the weight of the rider equally on the tube and a forward extension, which functions like the bow of a boat.

It is a further object of the within invention to provide means to propel and direct the vehicle formed by the frame and tube through the water. Accordingly, the frame is provided with a pedal-actuated propeller, a tiller and a rudder.

2

A still further object of the within invention is to provide a water vehicle for children which simulates the appearance of a boat. Thus, a front deck and a rear deck are mounted on the frame, and the front deck includes means for attaching a sail.

Other objects of the invention will become apparent upon reading the following specification and referring to the accompanying drawings in which similar characters of reference represent corresponding parts in each of the 10 several views.

In the drawings:

Fig. 1 is an elevational view of one side of a boat frame according to the within invention.

Fig. 2 is a top plan view of the embodiment shown 15 in Fig. 1.

Fig. 3 is a front elevational view of the embodiment of Fig. 1.

Fig. 4 is an elevational view of the other side of the 20 embodiment of Fig. 1.

Fig. 5 is an enlarged fragmentary view, partially broken away, of the pedal and drive arrangement shown in Fig. 4.

Referring now more particularly to the drawings, indicated generally at A is a preferred embodiment of a boat 25 frame according to the invention. Frame A is adapted to receive an inflated inner tube, such as the one indicated by the dotted lines at 45. The tube is mounted in the cut-out portion 35, better seen in Fig. 1 of the drawings, so that its diameter is in direct alignment with the horizontal extension of the frame and will project laterally on opposite sides thereof. The projection of the tube stabilizes the frame in much the same manner as a pair of pontoons or the outrigging of a canoe.

As best seen in Figs. 1 and 4, the tube receiving cut-out 35 is substantially U-shaped, and is defined at oppositely-disposed ends by concave margins 37 and 39. These margins have a radius of curvature slightly less than the radius of curvature of an inflated inner tube, and are spaced apart a distance slightly less than the tube's 40 diameter. When the resilient tube is placed in the cut-out and properly aligned with the frame, it is securely maintained in position. Provided on the upper margin of the frame within the area enclosed by the tube is a seat 43. The seat is positioned on the frame to locate the 45 operator centrally of the tube thereby evenly distributing his weight over the supporting surfaces of the tube and virtually eliminating the ability of the vehicle to capsize. In this regard the vertical extension 3 of frame A serves as a keel similar to that of a sail boat further stabilizing the vehicle.

Referring more specifically to the boat frame, it will be seen that fore and aft of the keel portion 3 the frame also comprises a bow 5 and a stern 7. The angularly-inclined bow 5 acts as a break water to decrease the resistance normally encountered by the tube when an attempt is made to propel it in water. Also, bow 5 gives a boat-like appearance to the frame, which appearance is enhanced by deck members 9 and 11 which project laterally on opposite sides of frame A and also function 50 to increase stability. The foredeck 9 may include a mast-receiving support 13, and when mast is mounted therein, the vehicle assumes the appearance of a sail-boat.

The vehicle as thus far described may be furnished 55 without mechanical propulsion means, and when such is the case, it may be propelled by treading water from a seated position. However, I have found that the device is put to more enjoyable use when provided with mechanical propulsion means to permit more rapid movement across the water. Accordingly, as best seen in Figs. 4 and 5, frame A preferably includes a pedal-actuated

ated drive generally comprising a propeller 27 mounted on a rotatable shaft 23. Shaft 23 may be journaled in a sleeve 21 attached to one side of frame A by holders 19. At the opposite end of the shaft is a pinion 29 which engages a pedal-driven gear 31 secured to pedal bar 33 for rotation when pedals 41, eccentrically mounted at the ends of bar 33, are actuated by the feet of the operator. Housing the gear 31 and pinion 29 are a pair of outwardly-extending plates 35 and 37 attached to the frame. Abutting these plates, which also act as bearings for the rotatable pedal bar 33, are a pair of sleeves 39, provided as stops to prevent lateral movement of bar 33. Thus, when the operator is positioned on seat 43, he may manipulate pedals 41 in a manner similar to his familiar wheel toys or bicycle. Such manipulation rotates gear 31 to drive pinion 29 and propeller 27 mounted on the end of rotatable shaft 21. As the weight of the operator is distributed evenly over the supporting surfaces of the tube, a minimum of water is displaced and the vehicle will glide smoothly and at a rate of speed commensurate with the operator's abilities.

Referring now to the stern end 7 of the vehicle, steering means is desirably provided to permit direction of the vehicle by the operator. The steering means includes a tiller 15 journaled in the end of frame A and attached to an arcuately-movable rudder pivotally mounted on pin 26. By actuating the tiller to right or left, the rudder will turn a like amount to change the course of the vehicle as desired.

In the operation of the device, the inner tube is inflated and fitted into cut-out 35 with the diameter of the tube properly aligned with the horizontal extension of frame A. The vehicle is then placed in the water. The operator may climb over the tube onto the seat or may enter the seat from beneath the tube. Then by manipulating the pedals and tiller, vehicle may be propelled and directed to transport the operator over the water.

Although the foregoing invention has been described in some detail by way of illustration and example for purposes of clarity of understanding, it is understood that certain changes and modifications may be practiced within the spirit of the invention and scope of the appended claims.

What is claimed is:

1. Means for mounting an inflated inner tube comprising: a frame; said frame having a horizontal extension greater than the outside diameter of an inflated inner tube and a vertical extension greater than the outside cross-sectional diameter of an inflated inner tube; said

frame defining a substantially U-shaped cut-out portion located between the vertical margins of said frame to receive an inflated inner tube normal to said frame and extended on opposite sides thereof; said cut-out portion terminating at oppositely-disposed ends in concave margins having a radius of curvature slightly less than the radius of curvature of said tube; said margins spaced apart horizontally a distance slightly less than the outside diameter of said tube.

2. Means according to claim 1 and in which a seat is mounted on the upper horizontal margin of said frame between said oppositely-disposed concave margins and inwardly from said concave margins a distance greater than the cross-sectional diameter of said tube.

3. The combination comprising: an inflated inner tube and a sheet of material to receive and maintain said tube therein; said sheet defining a substantially U-shaped cut-out between its vertical margins in which the oppositely-disposed legs of the cut-out are curved to conform to the outside radius of curvature of said tube and terminate at their upper ends in downwardly-extending flanges; said oppositely-disposed legs being spaced apart a distance slightly less than the outside diameter of said tube; said tube mounted in said cut-out so that the diameter of the tube is substantially in alignment with the horizontal extension of said sheet whereby said tube is securely maintained in position by said sheet and projects laterally on opposite sides of said sheet.

4. A water vehicle comprising in combination: a frame having a substantially U-shaped cut-out at the upper end thereof between the vertical margins of said frame; said U-shaped cut-out formed to snugly receive an inflated inner tube therein; an inner tube mounted in said cut-out and extending laterally on opposite sides of said frame; a seat mounted on the upper horizontal margin of said frame, normal to said frame and below the interior of said tube, whereby an operator may be supported on said frame inside said tube.

5. A water vehicle according to claim 4 in which the frame includes: pedal-actuated drive means mounted on said frame, a propeller at one end of said drive means; a rudder on said frame proximate said propeller; and a tiller journaled in said frame to actuate said rudder.
